UNITED STATES PATENT OFFICE.

HENRI J. HOUPERT, OF MAMARONECK, NEW YORK.

PISTON.

Application filed February 15, 1922. Serial No. 536,647.

To all whom it may concern:

Be it known that I, HENRI J. HOUPERT, a citizen of the United States, and resident of Mamaroneck, in the county of Westchester 5 and State of New York, have invented a new and useful Piston, of which the following is a specification.

The invention relates to pistons of internal combustion engines, and the object is to provide a simple and efficient construction affording universal pivotal movement between the piston and connecting rod, whereby numerous advantages in respect to manufacture, assembling and operation are secured. 10

15 The construction involves a pivoted yoke between the piston and a wrist-pin in the end of the connecting-rod, the yoke being pivoted to the piston on an axis at right angles to and offset from the wrist-pin.

20 In the accompanying drawings, illustrating a preferred embodiment of the invention:

Fig. 1 is a longitudinal section through a piston embodying the invention;

25 Fig. 2 is a longitudinal section at right angles to Fig. 1; and

Fig. 3 is a bottom plan, omitting the connecting rod and wrist-pin.

The head of the piston is marked 1 and 30 the skirt 2, these parts being preferably made integral, though this may be otherwise. Owing to the nature of the connection between the piston and the connecting rod, the skirt can be machined inside as well 35 as out, and the wall can be made exceedingly thin, as shown.

The upper end of the connecting rod 3 is pivoted on a wrist-pin 4, which can be of customary thickness, so that the piston 40 is interchangeable with one of ordinary construction, the connecting-rod being standard. The ends of this wrist-pin are not received in internal bosses on the skirt, as is usual, but in alined collars 5 formed on the lower 45 ends of the arms 6 of a bridge or yoke 7, the head of the connecting rod lying between these arms.

The yoke is formed centrally of its top 50 with a transverse head 8 which is turned down at the ends to form journals 9, constituting an upper pivot at right angles to the wrist-pin and offset therefrom. These journals are received in spaced bearings 10 carried by the head of the piston and close thereto. The yoke is thus capable of rock-

ing relatively to the piston, in a plane at right angles to the main pivotal movement of the connecting rod on the wrist-pin, the extent of the secondary rocking movement of the yoke being naturally slight. 60

The bearings 10 have screw stems 11 extending upward through the head of the piston, and are secured by nuts 12, which are sunk in recesses 13 in the upper surface afforded by bosses 14. Further security is 65 afforded by riveting over the ends of the stems, as at 15. In this way, the bearings or connection on the piston for the upper pivot is constructed separate from the piston head, and means are provided for attaching the same thereto; which is advantageous since it facilitates assembling and avoids drilling through the skirt. Manifestly the particular construction may be 70 varied.

The collars 5 are preferably split at the bottom and formed with perforated lugs 16 for clamping screws 17, whereby the wrist-pin is held. 75

With a piston made in accordance with my invention it will be evident that all side strain on the piston and cylinder walls is eliminated, with consequent reduction in wear. It also becomes unnecessary to square or aline the pistons, which is very important 80 with ordinary pistons and is frequently neglected. Since the inside of the cylindrical piston wall is entirely unobstructed, it can be machined all the way to the top, and because there is no strain on this wall, either 85 lateral or longitudinal, all longitudinal strain being transmitted directly to and from the head of the piston to which the upper pivot is connected, the said wall can be made very thin, as previously stated. 90

In operation the expansion is slight and uniform, due to the slight and uniform thickness of the wall, and consequently a very close fit is possible. This in turn entirely eliminates piston-slap, tends to eliminate smoking, and makes possible the use of a lesser number of rings than ordinarily (only one is shown), or the dispensing with them entirely. The wrist-pin being entirely enclosed, there is, of course, no opportunity for it to score the wall of the cylinder, and because of the introduction of the second pivot at right angles the wear on the wrist-pin is greatly reduced. Finally, the invention makes possible the production of cast- 100 105 110

iron pistons which are near in weight to aluminum, with all the wearing qualities of cast-iron.

It will be understood that I do not limit myself to the precise embodiment illustrated and that there may be changes in form, proportions and details.

What I claim as new is:

1. In an internal combustion engine and in combination with a connecting-rod and a wrist-pin in the end of said connecting-rod, a piston within which said wrist-pin is enclosed, a yoke engaging the ends of the wrist-pin and embracing the end of the connecting-rod, and a pivot connecting said

yoke with the piston above and at right angles to the wrist-pin.

2. In an internal combustion engine and in combination with a connecting-rod and a wrist-pin in the end of said connecting-rod, a piston within which said wrist-pin is enclosed, a yoke engaging the ends of the wrist-pin and embracing the end of the connecting rod, said yoke having journals forming a pivot above and at right angles to the wrist-pin pivot, and bearings on the interior of the head of the piston receiving said journals. 20 25

HENRI J. HOUPERT.
